UNITED STATES PATENT OFFICE.

ARCHIBALD BLACK, OF BROOKLYN, NEW YORK, ASSIGNOR, BY MESNE ASSIGNMENTS, OF ONE-HALF TO L-W-F ENGINEERING COMPANY, INC., OF COLLEGE POINT, LONG ISLAND, NEW YORK, A CORPORATION OF NEW YORK.

AEROPLANE-CONTROL SYSTEM.

1,395,254.

Specification of Letters Patent. Patented Nov. 1, 1921.

Application filed March 21, 1917. Serial No. 156,338.

To all whom it may concern:

Be it known that I, ARCHIBALD BLACK, a citizen of the United States, and a resident of Brooklyn, in the county of Kings, and in the State of New York, have invented a certain new and useful Improvement in Aeroplane-Control Systems, and do hereby declare that the following is a full, clear, and exact description thereof.

18 My invention relates particularly to an apparatus designed to control the lateral equilibrium of aeroplanes.

The object of my invention is to provide an apparatus by means of which the lateral equilibrium of an aeroplane may be controlled, and by means of which the aeroplane may be turned to the right or to the left, as desired. A further object of my invention is to provide an apparatus which is wholly subject to the control of the operator of the aeroplane, whereby he may at will elevate either side of the aeroplane and simultaneously depress the other side thereof, and in such a manner that the depression or elevation of either side of the aeroplane need not have any effect in accelerating or retarding the movement of the aeroplane at the side depressed or elevated. In other words, an object of my invention is to provide a device 25 by the operation of which a particular side of an aeroplane carrying the same may be elevated or depressed without affecting the speed of that side of the aeroplane, and which is so arranged that, if desired, the speed of either side of the aeroplane may be changed by the operation of said device. A further object is to provide a controlling apparatus for aeroplanes in which the vertical rudder is eliminated. Further objects of my 30 invention will appear from the detailed description thereof contained hereinafter.

While my invention is capable of embodiment in many different forms, for the purposes of illustration I have shown only one 35 form thereof in the accompanying drawings, in which—

Figure 1 is a front elevation of an aeroplane equipped with my invention;

Fig. 2 is a side elevation of the same;

50 Fig. 3 is a diagrammatic representation of the control system shown in its middle position;

Fig. 4 is a similar view of the same show-

ing it in position to elevate one side and depress the other side of the aeroplane, and

Fig. 5 is a similar view showing the same in position for turning the aeroplane to one side.

In the drawings I have shown an aeroplane having a fuselage 1, provided at each side of the fuselage with a stabilizer plane 2 and a rudder 3 extending rearwardly from the stabilizer planes. The horizontal rudder 3 may be controlled by the aeroplane operator in any suitable manner, as for example, by controlling cables 4 and 5 leading from brackets 6 and 7 attached to the rudder 3 and into the fuselage in proximity to the position of the operator. The operator of the aeroplane may be provided with a seat, not shown, in an opening 5^a in the top of the fuselage, from which point the control of the aeroplane may be effected. In the opening 5^a, there may be provided two coaxial juxtaposed hand-wheels 8 and 9 for controlling the lateral equilibrium and lateral turning of the aeroplane, the same being carried where they obviously may be seized and moved either separately or together, respectively on the sleeve 10 and a rod 11 which passes through said sleeve, and the sleeve 10 and rod 11 being shown as pivotally supported in a rectangular frame 12 having, for example, two cross-members 13 carried by a pivot 14 located on the interior of the fuselage. The sleeve 10 is shown as provided at its lower end with a gear 15 meshing with a gear 16 on a shaft 17 attached to a roll 18, pivoted in the frame 12, and the rod 11, as shown, carries a gear 19 meshing with a gear 20 on a shaft 21 carried by a roll 22, pivoted in the rectangular frame 12, the hand wheels being thus so placed and mounted that they can, when desired, be operated independently. An endless cable, or the like, 23 is shown as so arranged as to be doubled upon itself to form two loops 24 and 25, which are shown as wrapped around the roll 18 spirally. The loop 24 preferably passes over three pairs of idler wheels 26, 27 and 28, and the loop 25 preferably passes over one pair of idler wheels 29. Intermediate the wheels 28 and 29, the two portions of the cable 23 are shown as attached respectively to lever arms 30 and 31 secured respectively to planes 32 and 33.

supported upon a common pivot 34 which may be secured between pairs of struts 35 and 36, which extend between upper and lower supporting planes 37 and 38 that are secured to the fuselage 1. Other pairs of vertical struts, such as 39, 40, 41 and 42 secure said two planes 37 and 38 together, and wire stays 43 are provided at intervals between the struts. The struts 39 and 40 are provided with lower extensions 44 and 45 which, in the embodiment shown, lead to wheels 46 for supporting the aeroplane from the ground, obliquely arranged braces 47 and 48 being preferably provided to brace said wheels from the fuselage 1. The idler wheels 26 are preferably supported in the fuselage 1, and the idler wheels 27 and 28 are preferably supported from the supporting plane 37, while the idler wheels 29 may be supported upon the plane 38. At the other side of the aeroplane similar planes 49 and 50 are shown as provided upon a common pivot 51, supported between the struts 41 and 42, and as the controlling means for these planes 49 and 50 is shown as the same as the controlling means at the other side of the aeroplane, the details of the controlling means at this side of the aeroplane will not be described. The aeroplane may be provided with the usual motor 52 for driving a propeller 53.

In the operation of my invention, when the aeroplane is proceeding upon a level course, and it is neither necessary to control the lateral equilibrium nor turn to the right or the left, the planes 32, 33, 49 and 50 will be in the position as shown in Fig. 3. When, however, it becomes necessary for the aeroplane to turn to the right or to the left, one of the hand-wheels 8 and 9 will be operated so as to open those two of the planes, 32, 33, 49 and 50, which are located at the side toward which the aeroplane is to turn, as in Fig. 5. This will have the effect of retarding this side of the aeroplane so as to cause the aeroplane to turn in this direction. If for any reason it becomes necessary to elevate the side of the aeroplane away from which the aeroplane is turning, the rectangular frame 12 may be moved upon the pivot 14, the operating means thus moving as a unit, so as to elevate the controlling planes at the side away from which the aeroplane is turning and depress the controlling planes at the other side, the respective effects of this pivotal movement being thus substantially equal and opposite. This movement would be comprised of not only the movement shown in Fig. 4, but the movement shown in Fig. 5. If desired, also, in order to control the lateral equilibrium alone, and without retarding the movement of one side of the aeroplane, the planes 32, 33, 49 and 50 may be moved so that one pair thereof is elevated, while the other pair thereof is simultaneously and correspond-

ingly depressed, as shown in Fig. 4, through the pivotal movement of the frame 12 upon the pivot 14. If the aeroplane is to ascend or descend as a whole, the horizontal rudder 3 may be utilized by moving the same upwardly or downwardly by means of the cables 4 and 5.

While I have described my invention above in detail, I wish it to be understood that many changes may be made therein without departing from the spirit of my invention.

I claim:

1. In combination, an aeroplane having two pairs of rearwardly separable controlling planes, one of which pairs is located at each side of the aeroplane, and a common controlling means for the same comprising a swinging frame having two rolls connected by cables to said pairs of planes respectively, and independent handwheels on the frame for controlling said rolls. 80

2. In combination, an aeroplane having two pairs of separable controlling planes, a pivoted frame, a pair of rolls journaled in said frame each having cables connected to one of said pairs of planes, and independent hand wheels having concentric shafts respectively connected to said rolls. 90

3. In combination, an aeroplane having two pairs of separable controlling planes located on the two sides thereof, a pivoted frame, a pair of rolls journaled in said frame each having cables connected to one of said pair of planes, and independent hand wheels 100 having concentric shafts respectively connected to said rolls. 95

4. In combination, an aeroplane having two pairs of hinged controlling planes, a pivoted frame, a pair of rolls journaled in 105 said frame, each having a pair of endless cables wound around it and connected to one of the planes, concentric hand-wheels mounted on the frame and constructed to turn said rolls. 110

5. In combination, an aeroplane having two pairs of rearwardly separable controlling planes, one of which pairs is located at each side of the aeroplane, and a common controlling means for the same comprising 115 a swinging frame having two rolls, each connected by two endless cables to the planes respectively and concentric hand-wheels in the frame for turning the rolls.

6. In combination, an aeroplane having 120 two pairs of separable controlling planes, means for operating the planes comprising a pair of rolls each having cables connected to each set of planes, and independent hand-wheels having concentric shafts respectively 125 connected to said rolls.

In testimony that I claim the foregoing I have hereunto set my hand.

ARCHIBALD BLACK.
